UNITED STATES PATENT OFFICE.

LYTLE J. HUNTER, OF COVINGTON, KENTUCKY.

STATION-INDICATOR.

SPECIFICATION forming part of Letters Patent No. 658,778, dated October 2, 1900.

Application filed July 15, 1899. Serial No. 723,970. (No model.)

To all whom it may concern:

Be it known that I, LYTLE J. HUNTER, a citizen of the United States, and a resident of the city of Covington, in the county of Kenton 5 and State of Kentucky, have invented certain new and useful Improvements in Station-Indicators, of which the following is a specification.

This invention has for its objects the improvement of certain important features of 10 construction. These last-named features are shown and described in Letters Patent of the United States No. 610,271, dated September 6, 1898, granted to myself and one William 15 F. Peters, as joint inventors, and of which Letters Patent I am the sole owner.

The several features of my present invention and the various advantages resulting 20 from their use conjointly or otherwise will be apparent from the following description and claims.

In the accompanying drawings, making a part of this specification, and in which similar letters of reference indicate corresponding parts, Figure 1, Sheet 1, represents in perspective a portion of the car roof or deck, together with a station-indicator made according to my invention applied thereto. Fig. 2, same sheet, is a view of that portion of the 25 indicator which is at the left hand in Fig. 1, this view being partly in elevation and partly in section. Fig. 3 is an elevation of that end of the indicator which is at the left hand in Fig. 1 and which is above the car-roof. Fig. 30 4, same sheet, represents a transverse vertical section taken near the mid-length of the indicator and to the left of the electric lamp of the indicator, that face of the section being shown which faces toward the left of the 40 spectator when the latter is in front of the indicator. Fig. 5, same sheet, is a view in perspective of a portion of a detail of the indicator. Fig. 6, Sheet 2, is a view in perspective of the lamp chamber and reflector. Fig. 7, same sheet, is a perspective view of the removable roof. Fig. 8, same sheet, is a perspective view of the larger 45 (upper) portions of the station-indicator, the front glass being partially removed and broken off and a portion of the light-diffusing device being broken away the better to dis-

close the parts within the indicator. Fig. 9, same sheet, is a view of the upper portion of that end of the indicator which is at the right hand in Figs. 1 and 8. Fig. 10, same sheet, 55 is a view, partly in elevation and partly in section, of a portion of the shaft for operating the indicator and of the sleeve and the mechanism for locking the shaft.

I will now describe my invention in detail. 60 A indicates the usual car deck or roof. My station-indicator is located there. Usually there is in the roof a central raised portion A², and in such event the indicator is preferably located on the first or main deck A and 65 in front of the end of the raised deck A².

B indicates the upper portion of the end of a car, and C an upper portion of the side of the car.

No special construction of the car itself is 70 necessary for the application of my invention. The car may therefore be varied at will. All that is necessary for the use of my invention is a roof and the proper framework to support it.

Referring to my station-indicator, D indicates the base. Each side edge of this base is bent up, forming a flange D². (See Fig. 4.) There are vertical end pieces E E², piece E at the left-hand end of the indicator and 80 piece E² at the right-hand end of the indicator. These ends have flanges E³ near each edge. Each of the ends is secured to the bottom D by bolts or screws E⁵, respectively, passed through the holes E⁴ in the flange D² 85 and into or through the flange E³. Each edge of each end projects beyond the adjacent flange E³, forming a projection E⁶. The latter keeps the roof-cap G and the flange D² far enough away to enable the glass F to be 90 admitted between the flange B² below and the roof-cap G above on the one hand and the flange E³ on the other hand.

The back portion of the indicator forms an illuminating-chamber H. The back H² of this 95 chamber interiorly, at least, is curved, and for economy of construction it is altogether curved. H⁴ indicates the bottom and H³ the top of the chamber H. The front is open, but at the ends, top, and bottom is provided 100 with a flange H⁵ for enabling it to be readily secured to the front portion (already de-

scribed) of the indicator. Thus the bottom part H^4 of the flange fits over the back one of the flanges D^2 of the bottom D , and the top flange H^5 fits under the cap G , and the 5 end flanges $H^5 H^5$, respectively, fit flat against the adjacent flanges E^3 of the end pieces $E E^2$. The arched cap G not only fits over the upper flange H^5 of the back, but it also arches over the indicator and lops over in 10 front of the front projections E^6 and flanges E^3 of the ends E . Suitable bolts or screws, as G^2 , serve to hold the cap to the ends and back, substantially as shown. Thus the entire structure is compactly held together.

15 In the front chamber of the indicator is located the traveling indicator-strip J , rolled upon two parallel rollers K and L , duly journaled in the ends of the indicator. The upper one, K , of these rollers carries within it 20 a spring, which is secured at one end to the roller and at the other end to an axle or fixed journal of this roller, (in any well-known manner,) so that the spring always tends, when permitted, to wind the indicator-strip 25 J upon roller K and to always keep the indicator-strip taut between the rollers. The lower roller L is provided at one end with a bevel gear-wheel M , operated as hereinafter described.

30 The light is located in the illuminating-chamber. This light is preferably an electric (incandescent) one T , as shown, set at the middle of the chamber, the electric wires (conductors) coming through the opening H^6 35 in the bottom of the chamber H . In the roof of the chamber H and directly over the lamp is located an opening H^7 , closed by a screw-cap H^8 . Through this opening the lamp can be reached for repair, &c. The cap H^8 is readily removed and replaced.

40 A very advantageous and important device is a light-diffuser T^2 . This consists of a sheet of metal containing perforations T^3 , located in front of the lamp and extending a short 45 distance to each side of the mid-length of the sign. The lower end of the sheet being bent around forward beneath the roller L is brought up to the front portion of the bottom D , substantially as shown, and is there preferably fastened. The bevel-gear M engages a horizontal bevel gear-wheel N , connected to a shaft N^2 , rotating within a fixed sleeve P , whose lower end is preferably enlarged and contains in its bottom edge notches P^2 . 50

55 The lower end portion of this shaft N^2 is within a sleeve Q and is at its lower terminus provided with a square head Q^2 , which fits closely the angular passage in the sleeve Q . Within the sleeve and resting on the upper 60 edge of the head Q^2 is a spiral spring Q^5 , whose upper end bears against an interior abutment of this lower sleeve Q . Thus compressed it continually holds the lower sleeve Q against the upper sleeve P . The upper 65 part of the lower sleeve Q has one or more

teeth or fingers Q^3 , preferably located on a disk Q^4 and adapted to respectively engage notches P^2 of the sleeve P .

The indicator-strip J will contain the names of stations (terminals) at which the car is to stop. The operator of the car sets the indicator-strip so as to exhibit to view at the front of the indicator a station at which the car will stop. This he does by drawing down the rod Q , thus withdrawing the finger Q^3 70 from a notch P^2 and rotating the rod in the desired direction until the name of the proper station has been exposed to view. He then allows the spring Q^5 to lift the rod and cause the finger Q^3 to enter the notch P^2 , which is 80 adjacent to the finger. The station-name is thus set.

I have provided very convenient means for supporting the gear-wheel N and its accompanying shaft N^2 —to wit, a piece R receives 85 the shaft N^2 and directly supports the latter by upholding the bevel-gear N . This piece R contains side flanges R^2 , one on each side of the gear-wheel, and these flanges each carry a perforated lug or eye R^3 , whereby connection can be made with the roof. The piece R is also bracketed to the indicator-case by a bracket strip or piece R^4 . The flange R^5 of this strip permits its lower end to be securely 90 bolted to the piece R by a bolt R^6 , as shown. 95 This flange R^5 preferably fits in behind a shoulder R^7 on the piece R . The upper end of this bracket piece or strip R^4 carries a hook R^8 , having a double curve—viz., in the form of an ogee curve—and before the flange R^5 is secured to the piece R the hook is inserted in the slot E^7 in the end E of the case, and the brace R^4 is then secured to the piece R . In this way the bracket-piece R^4 securely binds 100 in a simple and effective manner the piece R to the indicator-case. The sleeve P is secured to the piece R preferably by a set-screw P^3 . 105

110 As heretofore mentioned, the front of the indicator is provided with the glass F , and this glass is slid in substantially as indicated in Fig. 8 and is held at the ends by the adjacent flange E^3 and the flange D^2 , projection E^6 , and the edge of cap G above. The glass is prevented from sliding out at the front of the right-hand end of the case (where no projection E^6 is admissible) by means of a locking-latch F^2 , pivoted at F^3 to the case and when allowed to drop taking the position 115 shown in Fig. 9.

120 When rain falls, there may some of it run between the glass F and the lower flange D^2 . In such event some water will collect upon the inside of the bottom of the casing, and unless it could be discharged the bottom part of the casing would fill with water and wet and soil the indicator-strip. I therefore provide a discharge-channel S , whereby the water is 125 conveyed off. It is to be noted that I purposely bring the lower roller and the indica- 130

tor-strip thereon near to the bottom for the sake of economizing room.

My improvements are economical of cost and advantageous in results.

5 What I claim as new and of my invention, and desire to secure by Letters Patent, is—

1. In a station-indicator, a casing having a bottom D provided with side flanges D², and the ends E having flange E³ and projection E⁶, and cap G, and glass F, and a locking-detent for keeping the glass from sliding out of place, substantially as and for the purposes specified.

15 2. In a station-indicator casing, the bottom D having flanges D², ends E having flanges E³, glass F, cap G, and rear illuminating-chamber having open front provided with flanges H⁵, engaging the adjacent flange D² and cap G, substantially as and for the purposes specified.

20 3. In the casing of a station-indicator, the bottom D provided with side flanges D², and the transverse gutter S, ends E E² having flanges E³ and glass F, whose ends are located between the flanges E³ and a flange D², and the cap G, lapping the glass and flange E³, substantially as and for the purposes specified.

25 4. In a station-indicator, a casing containing an indicator-strip and having rollers, and ends wherein the rollers are journaled, a beveled gear on one of the rollers, a horizontal beveled gear outside of the casing and meshing with the first-named gear, a vertical shaft connected to the horizontal gear, a piece R for supporting the latter gear, and a bracket-piece R⁴ having a double-curved hook engaging a slot in the end of the casing and connected at bottom to the piece R, and means for rotating the shaft of the horizontal gear, 30 and holding it at a given point of rotation, substantially as and for the purposes specified.

35 5. In a station-indicator, a casing containing an indicator-strip and having rollers, and ends wherein the rollers are journaled, a beveled gear on one of the rollers, a horizontal beveled gear outside of the casing, and meshing with the first-named gear, a vertical shaft connected to the horizontal gear, a piece R for supporting the latter gear, and a bracket-piece R⁴ having a double-curved hook engaging a slot in the end of the casing and connected at bottom to the piece R, the piece R having the side flanges R², and the eye-flanges R³, the side flanges R² and the bracket-piece R⁴ together covering the horizontal gear-wheel, and contributing to the support thereof, cap G having eyes G² and means for rotating the shaft of the horizontal gear, and holding it at a given point of rotation, substantially as and 40 for the purposes specified.

60 6. In a station-indicator, a casing, rollers therein, an indicator-strip connected with the rollers, ends of casing, a vertical beveled gear on one of the rollers, within the casing, a horizontal beveled gear engaging the first-named gear, vertical shaft connected to the last-

named gear, a sleeve embracing said shaft, a bracket-piece R for directly supporting the horizontal gear and its shaft and in turn hung from the casing of the indicator, the sleeve 70 having its upper end connected to the piece R, and extending down, and provided at its lower end with notches, a sleeve Q located on the shaft below the first-named sleeve, and capable of reciprocating with the length of 75 the shaft and constructed to compel the shaft to rotate with it, this sleeve Q having a finger rigidly connected thereto for engaging a given notch on the upper sleeve, and elastic means for elevating the sleeve Q and elastically 80 pressing it toward the upper sleeve, substantially as and for the purposes specified.

7. A casing for car-indicators comprising end portions having flanges, a bottom portion and a cap connected to and extending between said end portions at bottom and top of the casing, this bottom and this top being also provided with flanges spaced away from the flanges of the end portions, spaces being formed between the flanges of said end portions on one side and the flanges of the cap and bottom portion on the other side, substantially as and for the purposes specified.

8. A casing for car-indicators comprising end portions having flanges, a bottom portion 95 and a cap connected to and extending between said end portions at bottom and top of the casing and also provided with flanges spaced away from the flanges of the end portions, and a back portion formed with an 100 illuminating-chamber and having its edges held between the flanges of the end portions on one side and the flanges of the cap and bottom portion on the other side, substantially as and for the purposes specified.

105 9. In a car-indicator, the combination of a casing having an end portion formed with an opening leading to the inside of the casing, and with a projection exterior to the casing, a shaft mounted to turn in the casing, a gear-wheel on said shaft, an operating-shaft outside of the casing having its end journaled in the exterior projection of the end portion of the casing, a gear-wheel on said operating-shaft with one side of its periphery extended 110 through the opening in the end portion of the casing and in mesh with the gear-wheel on the shaft inside the casing, and a cover-plate 115 extended over the gear-wheel on the operating-shaft, substantially as and for the purposes specified.

120 10. In a car-indicator, the combination of a casing comprising end portions, a bottom portion, and a cap, a transparent sign held in the casing, a back portion for the casing secured to the back part of the casing and cut away upon its front side, and an illuminating device in said back portion, substantially as and for the purposes specified.

130 11. In a car-indicator, the combination of a casing, a shaft therein, a sign-curtain carried by the shaft, a projection on the casing,

a sleeve held by said projection and extended at an angle to the shaft therein, an operating-shaft extended through the sleeve, gearing between said operating-shaft and the curtain-carrying shaft, a part mounted for movement endwise along the operating-shaft, but held to turn in unison therewith, devices carried by said part and by the sleeve and adapted for engagement to hold the operating-shaft

against rotative movement in the sleeve, and a spring for holding said devices normally in engagement, substantially as and for the purposes specified.

LYTLE J. HUNTER.
